Primary Examiner — Mark A Goodwin(74) *Attorney, Agent, or Firm* — Tomlinson McKinstry,
P.C.(57) **CLAIM**

The ornamental design for a horizontal directional drill, as shown and described.

DESCRIPTION

FIG. 1 is a right side view of a horizontal directional drill, showing our design.

FIG. 2 is a back right top perspective view thereof.

FIG. 3 is a left side view thereof.

FIG. 4 is a back view thereof.

FIG. 5 is a front view thereof.

FIG. 6 is a back left top perspective view thereof.

FIG. 7 is a top view thereof.

FIG. 8 is a back view with a canopy removed.

FIG. 9 is a front view thereof with the canopy removed.

FIG. 10 is a right side view with the canopy removed; and,

FIG. 11 is a back right top perspective view with the canopy removed.
